a corporation of New York

Application January 5, 1950, Serial No. 136,980

13 Claims. (Cl. 68—5)

1

This invention relates to the dyeing of textile fabrics and other materials, and more particularly to an improved method and apparatus for photochemical dyeing of materials.

In my copending applications Serial Nos. 67,547 and 117,742, filed December 27, 1948, and September 24, 1949, respectively (both now abandoned), of which this application is a continuation-in-part, I have disclosed photochemical processes for dyeing materials, such as fabrics, by applying to the material an oxidizable dyestuff and a photosensitizer, and then exposing the material to controlled light radiation to oxidize and precipitate the dyestuff. According to the earlier of said applications, an indigosol dyestuff is combined with a light-sensitizing agent selected from the group consisting of cyanines, cyanates and thiocyanates, such as carbocyanine, isocyanate, or ammonium thiocyanate, which provides a light-energy absorption span much greater than that of the indigosol. The sensitizer serves to absorb and transform radiant energy from a wider band into energy of activation necessary for a rapid saponification reaction to occur, yielding the leuco form of the vat dye which is then oxidized rapidly to the insoluble colored dye form. The effect of the sensitizer, therefore, is a catalytic rather than a chemical one, in that it supplies under the influence of light in the visible spectrum a much greater energy of activation per unit of time than is absorbed by the unsensitized indigosol (sensitive mainly to the low wave lengths of light). With the greatly increased energy of activation afforded by the sensitizer, the saponification reaction and oxidation, with resulting precipitation of the vat dye, occur practically instantaneously when a textile coated or impregnated with the light sensitized indigosol is exposed to light.

According to the disclosure of the above-mentioned application Serial No. 117,742, the process involves applying to the material an oxidizable dyestuff, a photosensitive per-salt, such as potassium persulfate, and a photosensitizer such as uranyl acetate, uranyl nitrate or other uranyl salt or other material which fluoresces with a wave length similar to the uranyl salt under the action of the controlled light radiation to which the textile or other material is exposed. Thus, there is an absorption of radiated light energy by the uranyl salt and a formation of another energy level, with a subsequent transfer of this energy level to the potassium persulfate or other per-salt. This causes an accelerated decomposition

2

of the per-salt with the formation of nascent oxygen, whereby the dyestuff is oxidized very rapidly and uniformly upon exposure of the material to the light radiation.

5 In the practice of these processes, the photochemical reaction is effected rapidly under the influence of ultra-violet light radiation of high intensity and in the presence of moisture, and the present invention has for its principal object the provision of a method and apparatus by which the moisture can be provided effectively and expeditiously in a continuous photochemical dyeing operation.

According to the present invention, the fabric 15 or other material to be dyed is impregnated or coated with a solution or solutions of the dyestuff and the light-sensitizer and is then subjected to an atmosphere of finely divided moisture particles, which is preferably provided by 20 spraying water into a dye development chamber through which the fabric is conveyed. While the material is thus subjected to the atmosphere of moisture particles, it is exposed to intense ultra-violet light radiation by passing the light through this moist atmosphere to the material. In this way, the atmosphere of moisture particles or mist serves two functions. First, it distributes the moisture for the reaction uniformly and minutely throughout the light-exposed area of the material and in intimate contact therewith. Secondly, it serves as a cooling medium to prevent 25 burning or scorching of the material under the intense radiation from the light source.

In the preferred practice of the invention, the fabric or other material on which the dyestuff and light-sensitizer have been applied is moved 35 by a conveyor, such as a roller system, through a housing having a dye development chamber partly defined by a pair of opposed ultra-violet light-transmitting plates located in the housing, the fabric passing through the housing between the plates with the plane of the fabric parallel to but spaced from the plates. The light-transmitting plates are arranged between two opposed banks of ultra-violet lamps, each bank having reflectors facing the reflectors of the other bank. The housing is also provided with means for interposing moisture between the fabric and the light source or lamps, such means comprising 45 spray nozzles for delivering liquid in finely divided moisture particles between the opposed light-transmitting plates, on both sides of the fabric. An air draft is induced, as by means of a suction pipe, along the rear faces of the reflectors 50 to prevent overheating of the reflectors by

the lamps, but the spaces between the reflectors and the light-transmitting plates are shielded from the air draft so that the lamps in these spaces can operate at relatively high temperature for maximum efficiency. The development chamber between the light-transmitting plates is also shielded from the air draft, whereby the atmosphere of moisture particles or mist is maintained under substantially non-turbulent conditions. The light-transmitting plates are mounted in the housing so that they can be moved to permit access to the development chamber and the lamps.

For a better understanding of the invention, reference may be had to the accompanying drawings, in which:

Fig. 1 is a diagrammatic view of a preferred form of the new apparatus;

Fig. 2 is a front elevational view of the housing containing the dye development chamber of the apparatus illustrated in Fig. 1;

Fig. 3 is an enlarged front elevational view, partly in section, of the upper part of the housing shown in Fig. 2;

Fig. 4 is a view similar to Fig. 3 but showing the lower part of the housing;

Fig. 5 is a side elevational view of the dye development housing, showing one of the light-transmitting plates removed from the interior of the housing;

Fig. 6 is an enlarged vertical sectional view of one of the light-transmitting plates, showing details of the assembly of the plate components, and

Fig. 7 is a schematic view illustrating the electrical connections for the dye development lamps.

Referring to Fig. 1, the apparatus as there shown comprises a tank 10 or "padye" having a chamber 10a containing the dissolved dyestuff. The fabric F to be dyed is supplied from a roll 11, from which it passes continuously into the dye solution in chamber 10a and then upward between rollers 12 which squeeze the excess solution from the fabric. From the rollers 12, the fabric passes continuously to a second tank or "quetsch" 13 having a chamber 13a containing a solution of the dye sensitizer. After passing through the photosensitizing solution in chamber 13a, the fabric is drawn between rollers 14 which squeeze out the excess solution. The tanks 10 and 13 thus constitute means for applying the dye and the dye photosensitizer, respectively, to the fabric F.

Examples of the dye and photosensitizer solutions are as follows:

Example I.—Vat dyestuffs

Dye solution (chamber 10a).—Twenty grams of a potassium tetrásulfate derived from 3,3'-dianthrathydroquinonazine, obtained by oxidizing potassium sulfate of 3-amino-2-chloroanthraquinone (Indigosol Blue I. B. C.), are dissolved in 800 cc. of water at 140 to 160 degrees Fahrenheit. To this is added 25 cc. of a 20% ammonium thiocyanate solution and 4 grams of a wetting agent, such as sodium lauryl sulfonate.

Photosensitizer solution (chamber 13a).—Fifty grams of ammonium persulfate and 0.05 gram of uranium acetate dissolved in 1000 cc. of water.

Example II.—Sulfur dyestuffs

Dye solution (chamber 10a).—Twelve grams of the dyestuff prepared from 3-amino-carbazole converted into the O-mercapto and condensed with chloranil (tetrachloroquinone) (Hydron Blue R) are dissolved in 1000 cc. of water at

158-176 degrees Fahrenheit. To this is added 15 grams of sodium sulfide, 5 grams of sodium carbonate, and 1 gram of sodium hydroxide along with dispersing agents and materials for promoting the absorption of the dyestuff, such as sodium chloride or Glaubers salt.

Photosensitizer solution (chamber 13a).—Fifty grams of potassium persulfate and 0.05 gram of uranium acetate dissolved in 1000 cc. of water at 120° F.

Example III.—Diphenyl dyes

Dye solution (chamber 10a).—Forty grams of aminodiphenylamine (Diphenyl Black) are dissolved in 600 cc. of warm water containing 50 grams of lactic acid and 50 grams of acetic acid.

Photosensitizer solution (chamber 13a).—Fifty grams of potassium persulfate and 0.05 gram of uranium acetate dissolved in 1000 cc. of water at 120° F.

In addition to or in place of the uranyl salts mentioned above, dye sensitizers may be used which increase the range of spectral sensitivity by absorbing light energy at all wave lengths and transferring the energy to a level at which it can decompose the persulfate solution. Among these dye sensitizers are the isocyanine dyes, such as ethyl red, the carbocyanines, including pinacyanol, and a number of others such as kryptocyanine and neocyanine. Formulations employing the dye sensitizers with or without the uranyl sensitizers in the per-salt solution are submitted below. The dyestuff formulae may be the same as previously described.

Example IV

Potassium persulfate	g	50
Pinacyanol	g	0.005
Ethyl red	g	0.005
Water	cc	1000

Example V

Ammonium persulfate	g	50
Neocyanine	g	0.01
Water	cc	1000

The fabric thus saturated with the dye and photosensitizer solutions then passes through a chamber in a housing 15 of the dye development apparatus. As shown, the fabric enters the housing 15 from the top between a pair of conveyor rolls 16 and descends through the central part of the housing to the bottom where it passes between conveyor rolls 17. The fabric is maintained under tension as it descends from the rolls 16 to the rolls 17, so that it is maintained in a predetermined position in the housing. From the rolls 17, the fabric moves outward at the bottom of the housing and passes to a tank 18 or "quetsch" having a chamber 18a containing a washing bath. As the fabric passes through this chamber, the unreacted dyestuff is washed from the fabric, which is then drawn upward between squeeze rolls 19 for removing the excess liquid. The fabric then passes to a roll 20 on which it is wound.

Referring now to Figs. 2 through 6, the housing 15 of the dye development apparatus comprises opposed side walls 22, a front wall 22a and a rear wall 22b. The front wall 22a (Fig. 2) is provided with a rectangular opening which is normally closed by a door 23 hinged on the housing. The door has a handle 23a which can be swung back and forth to project or withdraw locking rods 23b slidably mounted on the door. The free ends of the rods 23b are adapted, when

the door is closed, to enter keepers 24 and 24a mounted on the front wall of the housing, so as to lock the door firmly in position for effecting an airtight seal.

The housing has a top 22c supporting a pair of spaced angle-iron members 25 which extend parallel to each other along the front and back of the housing and serve to mount the conveyor rolls 16. The latter are journalled between the members 25, and one of the rolls 16 is driven from a driving shaft 16a through a belt 16b. The lower rolls 17 are journalled between front and rear members 26 extending between legs 27 which support the housing. One of the conveyor rolls 17 is driven from a shaft 17a through a belt 17b. The drive shafts 16a and 17a are rotated at constant speed from a motor (not shown).

The housing 15 is open at the bottom, except for a partial bottom 22d extending along the sides of the housing from front to back. The central part of the housing interior communicates at the bottom with atmosphere through the open sides between the legs 27, as shown at 28 in Fig. 5. A perforated bottom plate 29 mounted below the housing and the conveyor rolls 17 (Fig. 5) serves to permit drainage of a liquid condensate from the interior of the housing, as will be described in greater detail presently.

Within the housing are opposed partitions 30 extending from front to back and forming directly above the partial bottom 22d a pair of closed chambers 31. Lamp reactors 32 are arranged in two vertical rows in each of the chambers 31, where they are mounted on the partition 30. The reactors are electrically connected to mercury-vapor or ultra-violet lamps 33 and 33a arranged in a pair of opposed vertical banks in the space between the partitions 30. As shown particularly in Fig. 5, the lamps 33 and 33a are of the quartz tube type, the tubes extending horizontally in the housing from front to back. The two banks of lamps 33 and 33a are provided with configurated plates 34 and 34a, respectively, extending from the front to the back of the housing and forming individual reflectors for the lamps, the reflectors of one lamp bank being opposed to and facing the reflectors of the other bank. The reflector plates 34 and 34a may be secured to the rear wall 22b of the housing and serve to support the mercury vapor lamps within the elongated recesses formed by the individual reflectors. Between each reflector plate and the fabric F is an ultra-violet light-transmitting plate 35 which is spaced slightly from the adjacent reflectors. The two plates 35 are disposed vertically in the housing, where they extend in parallel spaced relation from front to back. Each plate 35, as shown particularly in Fig. 5, comprises a frame in which panels 35a of quartz are mounted, the panels being held by angle-iron members 35b extending across the frame from one side to the other. As shown in Fig. 6, the panels 35a in one horizontal row are seated on the inwardly extending horizontal leg of a member 35b, and a thin stainless steel strip 35c is welded to the outer vertical face of this member 35b and extends upward along vertical H-bars 35d located between the adjoining vertical edges of adjacent panels. Asbestos tape (not shown) may be inserted between the strips 35c and the H-bars 35d. The strips 35c are silver-soldered along their upper edge, as shown at 35e, to create a waterproof seam. The lower edge of the strip 35c rests upon the upper edge of the underlying H-bars 35d which, in turn, rest upon the outwardly extend-

ing horizontal part of the next lower angle-iron member 35b. Thus, each horizontal row of panels is staggered with respect to the adjacent upper and lower rows. Since quartz plates are generally available in only small sections, I find that composite plates 35 of adequate area can be assembled conveniently in the manner described, to make the composite plates substantially airtight.

The frame of each composite plate 35 is provided at the top with U-shaped brackets 35f on which rollers 35g are mounted. The rollers of each plate 35 are supported on a track 36 which extends from the rear of the housing through a movable section 22e forming part of the front wall of the housing. At their inner ends, the tracks 36 are suspended from brackets 36a secured to the top 22c of the housing, and at their outer ends the tracks are suspended from the ceiling (not shown) by rods 36b. Thus, the composite plates 35 are suspended from the parallel tracks 36, on which they are adapted to be rolled independently of each other from the interior of the housing when the door 23 is opened, as shown in Fig. 5. When one of the composite plates is rolled from the housing along its track 36, the corresponding housing section 22e is moved outwardly in front of the plate and along the track; and when the plate is rolled back into the housing, the corresponding plate 22e is replaced to complete the closure of the front of the housing after the door 23 is closed. The plates 35 are guided at their lower edges by angle-iron members 37 supported between cross pieces 38 at the bottom of the housing.

It will be observed that the composite light-transmitting plates 35 define between them a chamber 39, which may be referred to as the dye development chamber. The fabric F, guided by the conveyor rolls 16 and 17, passes vertically through the central part of the development chamber 39, which it enters through a slot 40 in the housing top 22c. As the fabric passes through the chamber 39, its plane is parallel to the opposing plates 35 but spaced therefrom.

In the space between the fabric F and each plate 35 is a spray system comprising a liquid supply pipe 42 and branch pipes 42a and 42b of different lengths which extend inwardly into the chamber 39 from the lateral edge portions of the plate 35. The branch pipes 42a and 42b terminate in spray nozzles 42c which are adapted to distribute the liquid in a very fine spray throughout the chamber 39 on both sides of the fabric. As shown in Fig. 5, the main pipe 42 on each side of the fabric is mounted on the frame of the adjacent plate 35 by means of straps or brackets 43. A flexible hose (not shown) is connected to a nipple 42d at one end of each pipe 42 to supply the water or other liquid from a suitable source. It will be understood that the spray system forms a means for interposing moisture between the moving fabric F and the lamps or light sources 33-33a.

The rear wall 22b of the housing is formed near the top with air outlet openings 45 which lead from the spaces between the partitions 30 and the plates 35 to a manifold 46 (Fig. 5). The manifold 46 is connected to a suction pipe 47 for inducing an air draft through the open bottom of the housing and upward through the space between each reflector plate 34-34a and the adjacent partition 30, as shown by the arrows in Figs. 3 and 4. By means of this forced air draft, the reflectors are prevented from being overheated by the lamps 33-33a. Due to the close

spacing between the reflectors and the adjacent quartz plates 35; the lamps are shielded from the air draft so that they can operate at the relatively high temperature required for maximum efficiency. The air draft is excluded from the development chamber 39 by means of baffles 48 extending from the front to the rear of the housing along the upper parts of the quartz plates 35 at opposite sides of the fabric F, as shown in Fig. 3. In this way, the air draft induced by the suction pipe 47 is prevented from dispersing the fog or spray introduced into the chamber 39.

The fabric is delivered to the upper conveyor rolls 16 over a guide roller 49 and is withdrawn from the dye development apparatus at the bottom along a guide roller 50. In some cases, however, it may be desirable to convey the fabric through the housing from the bottom to the top, and so I provide additional guide rollers 49a and 50a to be used when the direction of travel of the fabric is to be reversed, in which case the fabric enters the housing from the lower conveyor rolls 17 and leaves the housing by way of the upper conveyor rolls 16.

The mercury vapor lamps 33-33a may be electrically connected to their corresponding reflectors 32 as illustrated in Fig. 7. As there shown, the lamps in each bank are divided into three sections, and the sections in the two banks are connected at opposite terminals by wires 52-53 and 52a-53a, respectively, leading to a current source 53 for energizing the lamps.

In preparing the apparatus for operation, the door 23 is opened to enable the leading end of the fabric F to be drawn downward manually from the conveyor rolls 16 through the development chamber 39 to the conveyor rolls 17, from which the end of the fabric is then passed along the guide roll 50 and the rollers associated with the washing tank 18, to the delivery roll 20. When the door 23 has been closed, the apparatus is ready to be operated by starting the liquid flow to the pipes 42 of the spray system, starting the conveyor rolls 16 and 17, and energizing the lamps 33-33a.

As the fabric moves through the housing 15, after receiving the dye and photosensitizer solutions from tanks 10 and 13, it is subjected on both sides to an atmosphere of finely divided moisture particles introduced into the development chamber 39 by the spray system. At the same time, it is exposed on both sides to the intense light from the mercury vapor lamps 33-33a, which emit light radiation between 2200 and 7500 angstrom units. The ultra-violet light from these lamps (and their reflectors) passes through the plates 35 and the confined atmosphere of moisture particles, which form a mist or fog, to the opposed sides of the fabric. The atmosphere of mist or fog in which the moving fabric is thus enveloped provides the moisture for the photochemical reaction and also enables the use of intense radiation without burning or scorching the fabric, which is preferably exposed to a temperature no higher than about 90°-100° F. in chamber 39. In this way, an exposure period in the order of a few seconds or less is generally sufficient to decompose the photosensitive per-salt solution and thus yield the oxygen necessary to oxidize the dyestuff and precipitate it as a colored, light-fast and water-insoluble substance on or within the fibres. Accordingly, the fabric may be moved rapidly through the entire apparatus, from the supply roll 11 to the delivery roll 20, by the conveyor comprising the various

rollers. To permit observation of the fabric passing through the dye development housing 15, the door 23 and the side walls 22 may be provided with port-holes, covered with ruby-red 5 Plexiglas shields 55 and 56.

The quartz panels 35a of the light-transmitting plates 35 are arranged with their vertical edges offset laterally from each other along the fabric path, as shown in Fig. 5. The vertical seams between adjacent panels are thereby prevented from cutting off a large part of the light radiation to any portion of the fabric passing through the dye development chamber. By mounting the branch pipes 42a and 42b of the spray system in line with the horizontal seams between the panels 35a, the pipes are prevented from cutting off any appreciable amount of light radiating to the fabric. While some of the light radiation is necessarily lost in passing through the plates 35 and the artificial fog created in the dye development chamber, the amount is small as compared to the total radiation from the lamps. The latter are selected to provide an intense radiation, and for this purpose I have found that General Electric vapor lamps of the type 30-UA-7 (615-705 v., 6.1 amps.) are satisfactory, particularly when arranged in opposed banks as described and illustrated.

In conveying the fabric through the apparatus, some provision should be made for maintaining the fabric under substantially constant tension, in spite of shrinking or stretching of the fabric as it is being processed. Since devices for counteracting changes in fabric tension, while it is being conveyed by rollers, are well known, I have not disclosed such a device in detail. However, I have illustrated generally in Fig. 1 a pair of tension-compensating rollers 58 and 58a associated with the dye and sensitizer tanks 10 and 13, respectively, these rollers being arranged to move up or down to counteract changes in the fabric tension. Similar tension-compensating devices may be located at other parts of the apparatus to prevent excessive or insufficient tension in the fabric during the processing.

The condensate resulting from the artificial fog in chamber 39 is discharged through the open bottom of the housing and through the underlying perforated plate 29, from which it passes to a suitable drain.

It is to be understood that the invention is not limited to the dyeing of fabrics but is applicable to other materials as well.

I claim:

1. Apparatus for treating textile fabrics and other materials, to which a photosensitive dye has been applied, which comprises a pair of opposed ultra-violet light-transmitting plates, a conveyor for moving the material continuously in a path between but spaced from said plates, a source of ultra-violet light located near each plate at the side thereof remote from said path, a liquid supply pipe, and a spray system connected to said pipe for introducing moisture particles between said plates and having spray outlets located on each side of the moving fabric between said path thereof and the adjacent transmitting plate.

2. Apparatus according to claim 1, comprising also reflectors adjacent the light sources and facing said plates and path, the plates and reflectors forming substantially closed spaces for the

3. Apparatus according to claim 1, comprising also reflectors adjacent the light sources and facing said plates and path, the plates and reflectors forming substantially closed spaces for the

light sources, and means for inducing an air draft along the reflectors outside said spaces.

4. Apparatus for treating textile fabrics and other materials, to which a photosensitive dye has been applied, which comprises a housing, ultra-violet lamps arranged in opposing banks in the housing, ultra-violet light-transmitting plates arranged in opposed relation in the housing between said banks and forming a passage between the plates, opposing plates in the housing forming reflectors for the lamps, said lamps and light-transmitting plates being located between the reflector plates, a conveyor for moving the material continuously along said passage in a path between but spaced from the light-transmitting plates, a liquid supply pipe, and a spray system connected to said pipe for introducing moisture particles into the spaces between said path and the light transmitting plates.

5. Apparatus according to claim 4, in which the reflector plates form with said light-transmitting plates substantially closed spaces for the lamps, the housing having side walls forming with each reflector plate an air passage behind the reflectors, and means for inducing an air draft through each air passage to cool the reflectors.

6. Apparatus according to claim 4, in which each light-transmitting plate includes a frame and light-transmitting panels supported in the frame with the panel edges offset laterally from each other along said path.

7. Apparatus according to claim 4, comprising also means for movably mounting the light-transmitting plates in the housing, to permit access to said passage and lamps.

8. Apparatus according to claim 4, comprising also a spray system mounted on the light-transmitting plates and operable to introduce moisture particles into said passage.

9. Apparatus for treating textile fabrics and other materials, to which a photosensitive dye has been applied, which comprises a housing having openings at the top and bottom, rollers at the top and bottom of the housing for conveying the material through the housing in a vertical path, ultra-violet lamps arranged in opposing vertical banks in the housing, reflectors for the lamps and positioned in the housing to face said path in opposed relation, ultra-violet light-transmitting plates in front of the

reflectors and disposed at opposite sides of said path, a liquid supply pipe, and a spray system in the housing connected to said pipe for introducing moisture particles between said path and the plates.

10. Apparatus for dyeing lengths of textile fabrics and other materials, which comprises means for applying the dye and a dye photosensitizer to the material, a source of ultra-violet light, a conveyor for moving the material in a path from said applying means to the region of the light source to expose the material to said light, an ultra-violet light-transmitting plate interposed between the light source and said path but spaced from said path, a liquid supply pipe, and means connected to said pipe for introducing moisture particles into the space between said path and the plate and in contact with the material.

11. Apparatus according to claim 10, comprising also a housing forming a development chamber having inlet and outlet openings for the material, said housing containing the light source and said moisture interposing means.

12. Apparatus according to claim 10, comprising also a reflector adjacent the light source and forming with said plate a substantially closed space for the light source.

13. Apparatus according to claim 10, in which 30 said moisture-introducing means are mounted on the light-transmitting plate, the apparatus also comprising a movable mount for said plate, whereby the plate and the moisture-introducing means are movable into and out of operative 35 position relative to the material path.
